UNITED STATES PATENT OFFICE.

DANIEL E. HALL, OF BEVERLY, MASSACHUSETTS, ASSIGNOR TO UNITED SHOE MACHINERY COMPANY, OF PATERSON, NEW JERSEY, A CORPORATION OF NEW JERSEY.

NAIL-DRIVING MACHINE FOR BOOTS AND SHOES.

1,115,529.

Specification of Letters Patent.

Patented Nov. 3, 1914.

Application filed June 19, 1908. Serial No. 439,325.

To all whom it may concern:

Be it known that I, DANIEL E. HALL, a citizen of the United States, residing at Beverly, in the county of Essex and State 5 of Massachusetts, have invented an Improvement in Nail-Driving Machines for Boots and Shoes, of which the following description, in connection with the accompanying drawings, is a specification, like 10 letters on the drawings representing like parts.

This invention relates to nailing machines.

Although capable of general use, the invention is particularly intended for the use 15 of repair shops and small establishments where custom work is done or where boots and shoes are made in a limited way.

To the above end, the invention includes 20 among its important features of novelty, the provision of a hopper or nail holder having means for holding a plurality of different kinds or sizes of nails, and co-operating mechanism for selecting, at the 25 will of the operator, any one of said kinds or sizes; work-feeding mechanism; gaging means for regulating the distance apart of the nails; means for regulating the driving distance in from the edge of the work; 30 gaging means for regulating the driving of the nails across the butt of the sole; nail-feeding mechanism; special nail-selecting mechanism; means for regulating the depth of driving, etc.

The constructional details of my invention will appear more at length from the following description read in connection with the accompanying drawings in which I have shown a preferred embodiment of 40 my invention.

In the drawings; Figure 1 shows my machine in side elevation; Fig. 2 is a top plan view thereof; Fig. 3 is an enlarged detail of the upper portion of the machine partly 45 broken away and sectioned for clearness of showing; Fig. 4 is a broken detail in rear elevation of the hammer operating mechanism; Fig. 5 is a sectional detail taken at the point 5 of Fig. 4 looking down on the 50 lifting lug and tripping cam of the hammer mechanism; Fig. 6 is a perspective view of the lifting lug; Fig. 7 shows in side elevation the movable nozzle and connected parts, and in longitudinal section the hopper, in its proper position with relation to

said nozzle; Fig. 8 is a fragmentary view of the nozzle in rear elevation; Fig. 9 is a fragmentary view in top plan of the parts shown in Fig. 7; Fig. 10 is a plan view of a portion of the feeding mechanism; and 60 Figs. 11 and 12 show respectively in side elevation and top plan, a modified gaging mechanism.

In custom shops and repair shops (and, for that matter, in regular shoe factories), 65 it is often desirable to have the opportunity of selecting from a variety of tacks or nails, but the usual nail driving machine is provided simply with one hopper or receptacle which carries a single kind or variety of 70 tacks and nails to which the operator is limited. Accordingly the various features of my invention contained and embodied in my machine center around the novel idea of having a plurality of independent pockets 75 or receptacles for a corresponding variety of nails. The arrangement is such that the nails maintain themselves at all times in readiness for feeding forward in position to be driven, whenever the nozzle is turned to 80 such a position as to drive a particular tack, the selector being brought into play at the same moment for selecting the given tack desired. The size of the hopper and the number of divisions or pockets therein will 85 correspond to the requirements of any given place or use. As herein shown, I have provided a hopper 1 having three pockets 2, 3 and 4 inclined as clearly shown in Figs. 1, 2, 7 and 9, each pocket having converging 90 sides and a groove or slot 5 in its bottom to direct the nails 6 down to the nozzle 7 of the machine. Above the slot or nail passage 5 I provide a vertical plate 8 normally having its bottom edge converging slightly 95 toward the lower end of the nail-way or passage 5 and adjustable by means of a screw 9 bearing against an inclined edge 10, and operating to prevent the nails from jarring out of the slot or passage 5. This plate 8 also prevents the nails from feeding down 100 to the nozzle too rapidly and serves in general to keep the nails in place and restrict them to their proper movement and operation. Above the hopper 1 is a hammer or actuator 11 for operating a nail driver 12, said nail driver having a plate or washer 13 resting on top of the actuator 11 which is provided with a slot 14 for the free movement therein of the driver 12 which recipro- 105 110

cates in the head 15 formed on the forward end of the hopper 1. The actuator 11 is in the form of a lever pivoted on an axle or bearing 16 mounted in separated ears 17, 5 Fig. 4, extending from the upper side of the hopper or head of the machine which is secured by sleeves or collars 18 formed integrally with the hopper or head of the machine and parts 19 to the upper ends of 10 separated rods 20 and 21, see Figs. 1 and 2, secured fast at their lower ends in a suitable base 22. Between the branching arms of the actuator or lever 11, is a hub or block 23, and depending integrally from said hub 23 15 is an arm 24 pivoted at 25 to a toggle link 26 pivoted at 27 to a reciprocating rod 28 slidingly supported in the base 22 and engaged at its lower end by the grooved upper surface 29 of the inner end of a treadle 20 30. The rods 20, 21 and 28 are slidingly mounted in the block like end 31 of a heavy arm 32 which carries a work-support in the form of a horn 33. The latter has a limited downward yielding movement by reason of 25 a spring 34 contained in a cavity formed therefor in the work-support, see Fig. 1, said spring engaging the work-support at its upper end and a stud 35 at its lower end, about which the work-support is free to 30 swing, being retained by a pin 36 passing through a reduced portion 37 of said stud. The block-like end 31 of the arm 32 serves also to retain together the supporting rods 20, 21, and the lifting rod 28 in mutually 35 supporting relation, being itself normally held yielding upward against a stop 38 by a spring 39 on the rod 28 against the pressure of springs 40 on the rods 20, 21, (to operate as presently described). In a 40 recess formed in the hub or block 23, see Figs. 3 and 4, I mount two sliding lifting blocks or lugs 41 held outward by a spring 42. Each lug has at its outer end an inclined surface 43 and an overhanging part 45 44 the latter being in position to engage a shoulder 45 on the rear underside of the adjacent arm or part of the actuating lever 11, and the inclined surface 43 being in position to engage the inclined face 46 of a 50 stationary cam 47 projecting inwardly from the adjacent stationary ear 17. Thus when the treadle is depressed the rod 28 and toggle link 26 operate to swing the arm 24 forward on its pivot 16, thereby lifting the actuator lever 11 by the engagement with its shoulders 45 of the ends 44 of the lugs 41, and as the said actuator lever 11 is raised by the said forward swinging movement of the arm 24, the lugs 41 are moved backwardly as 55 60 their inclined faces 43 slide along the cam surfaces 46, until the projections 44 escape from the shoulders 45, whereupon the actuator lever or hammer 11 is instantly and powerfully swung downward by a powerful spring 48 adjustably secured by a set bolt

49 to a stationary part 50 at one end and resting on a cross bar 51 of the lever or hammer 11 at its other end. As soon as the treadle is released, the spring 39 swings the arm 24 downwardly whereupon its lugs 41 70 are automatically pressed by the spring 42 to their outward position ready again to lift the lever or hammer 11. As the hammer went up, it lifted the driver 12 by engagement with the plate 13 thereof, and as it went down, it correspondingly forced said driver downwardly by engagement with a collar 52 adjustably clamped at 53 on said driver 12. The adjustment of the collar 52 serves to regulate the depth to which the 75 nails are driven into the shoe. A block 54 of fiber or leather is preferably interposed above the head 15 for partially relieving the latter of the driving shock in the absence of a nail. 85

The nozzle 7 is removably mounted within the head 15, and is also free to turn or rotate on the driver, being automatically locked in desired position by a bolt 55 normally held forward by a spring 56 which is provided with a projecting thumb piece 57 at its upper end to enable the operator readily to release the bolt from engagement with the nozzle so that the latter may be removed if desired. The nozzle is provided with a groove 58 to coöperate with the pointed end of the bolt 55 to prevent the nozzle being accidentally released, and in said groove are depressions 59 properly located and spaced apart to lock the nozzle in alignment with any given nail passage of the hopper when turned to that position. For this purpose the nozzle is provided with a handle 60, see Fig. 9, by which it may be turned. The nails or tacks in each pocket 100 of the hopper are normally held back or controlled by a light spring 61 carried by an upwardly projecting pin 62 so as to bear slightly but with sufficient force against the adjacent column of nails to prevent 105 their falling or sliding down of their own accord. The nozzle is provided at its rear side with a vertical slot 63 leading to the nail passage 64 thereof and in this slot is mounted or reciprocated, a selector or pivoted pick-off 65 pivoted on a stud 66 carried by the upwardly extending arm or plate 67 of a foot or work-rest 68 arranged to slide vertically in a groove 69 in the nozzle against the resistance of spring 70, said stud 66 and a similar stud 71 traveling in slots 72 for keeping the parts steady. The adjacent portion of the nozzle is cut away up to a point 73 so as to permit the projecting overhanging shoulder 74 of said work-rest 110 120 to move up to that extent, and the pick-off or selector 65 is provided with a shoulder 75 to engage a pin 76 which operates at the right moment to swing the pick-off on its pivot 66 and thereby carry a nail into driv- 125 130

ing position. The pick-off has a reduced point 77 for entering the track or nail passage 5 and is provided with an inclined upper edge 78 down which the selected nail 5 may slide, so that as the pick-off 65 rises, its point enters behind the foremost nail and deflects said nail down the surface 78 just as the pick-off is forcibly swung forward by the engagement of its shoulder 75 with the 10 pin 76. The part 68 of the work-rest carries a feed-wheel 79 provided with sharp teeth to engage the edge of the work and feed it along at the proper moment. This wheel is loosely mounted on the hub 80 of a post 81 15 provided at its upper end with a crank or offset arm 82 having a roll 83 in position to travel up an oblique surface or way 84 of a block 85 adjustably supported by a thumb screw 86 in a slot 87 of a gage arm 88 extending out laterally from the nozzle. The 20 arm 88 is preferably vertically, adjustable by a screw 89 on a projection 90 extending laterally from the nozzle. The beveled surface 84 of the block 85 slopes or inclines at 25 a steeper angle at its forward edge than at its rear edge, the latter being indicated in Fig. 8 at 91, so as to give a varying throw or turn to the post 81. A scale 92 indicates to the operator the adjustment of 30 the block 85. The wheel 79 is hollow and provided on its inside with teeth 93 engaged by a pawl 94 controlled by a spring 95 and pivoted at 96 to an arm 97 fast on the hub 80 or post 81, and the latter is held 35 in constant engagement with the block 85 by a spring 98. Thus each time the work-rest 68 is raised, the post 81 is caused to rotate by the engagement of its roll 82 with the inclined surface 84, this rotation carrying 40 the pawl forward in a direction opposite to the arrow, Fig. 10, and then as the work-rest is lowered, the spring 98 and engagement of the pawl 94 with the teeth 93 of the feed-wheel 79 cause the feed-wheel positively 45 to turn in the direction of the arrow and feed the work. The distance of this feeding movement, and hence of the spacing apart of the nails driven into the shoe, is regulated by the adjustment of the block 50 85 along the scale 92. A scale 99 is provided on an arm 100 projecting on the rear side of the work-rest to indicate to the operator the distance from the edge of the sole at which the nails will be driven. The 55 arm 100 is slotted at 101 so that, upon loosening a thumb nut 102 which passes through said slot into the post 81, said post and the feed-wheel may be slid along said slot 101 and thereby turned up out of the 60 way whenever it is desired to nail across the butt of a sole. The rest 68 then bears on the shank and end of the butt so as to gage the distance in that the nails are driven, being spaced by the eye relatively to the gage 65 marks 103.

In Figs. 11 and 12, I have shown a slightly different construction of edge gage and feed-wheel, the edge-rest consisting of a wheel provided with a series of concentric space indications 104, 105, 106, etc., alike for each 70 series, but the series differing from each other and the coöperating pointer or indicator 107 slotted at 108 so as to be radially adjusted to indicate for any one of said series desired and clamped between a post 109 extending upwardly from the wheel and a thumb nut 110. An opposite thumb nut 111 serves to clamp this mechanism in position on the part 100 the same as the feed-wheel 79 is clamped thereon. 75

In use, the operator places a shoe over the horn or work-support 33. He then depresses the treadle 30 which raises the rod 28 and thereby lifts the horn 33 and shoe against the work-rest 68, the operator at the same 80 time moving the shoe against the edge gage or feed-wheel 79. The continued upward movement of the rod 28 swings the arm 24 forward on the axle or pivot 16, and causes the lifting lugs 41 to lift the hammer lever 90 11 and thereby the nail driver 12. The same lifting movement of the rod 28 acts through the horn 33 to lift the work-rest 68 and thereby actuate the pick-off 65 to pick off the forward nail from the nail passage 95 or slot 5 and carry it into the nozzle passage 64 immediately beneath the nail driver 12. Just as the nail reaches this position, the rod 28 has raised the hammer 11 sufficiently to cause the lifting lugs 41 to be wedged out 100 of engagement with said lever by the cams 46 whereupon the heavy spring 48 instantly depresses the hammer 11 which, by its engagement with the collar 52, drives the driver 12 down with a hammer-like blow 105 thereby driving and clenching the nail on the cup-ended horn. As the operator releases the treadle, the springs 40 lower the work-support or horn 33 and as the work-rest 68 correspondingly lowers, the spring 110 98 rotates the feed-wheel and positively feeds the work along on the horn the distance to which the feeding mechanism has been set. This nail driving operation and work feeding movement succeed each other 115 in rapid repetition according to the speed with which the operator actuates the treadle. If at any time another kind or size of nail is desired, the operator simply turns the handle 60 so as to bring the nozzle into line 120 with the proper pocket or division of the hopper containing said nails so that the latter may be selected for the next drive. For example, in driving nails into a heel, it is frequently desirable to have a row of heavier 125 nails on one side of the heel than on the other, and this selection may be accomplished at any moment without stopping the regular driving operation of the machine. If a nail should get misplaced or if for any 130

other reason it is desired to inspect the nozzle or feeding mechanism, it may quickly be done by simply pressing back the thumb piece 57 of the spring 56 and pulling off 5 from the driver the nozzle and the mechanism carried by said nozzle. The nails are kept fed down continually to the lower end of the hopper by the operation of the latter. And for this purpose, I have provided the 10 two slender rod supports 20, 21, which, being spaced apart as indicated in Fig. 2, and being long and slender, produce a continuous trembling or vibration of the hopper each time the hammer 11 descends.

15 It will be understood that I am not limited to the constructional details herein shown otherwise than as by any given claim, inasmuch as many changes and substitutions may be resorted to without departure from 20 the spirit and scope of my invention. Also the latter is new in various subcombinations without using the entire organism, as is further pointed out in the claims.

Having described my invention, what I 25 claim as new and desire to secure by Letters Patent of the United States is:

1. In a nail-driving machine, nail-driving mechanism including a driver combined with a plurality of nail-holding receptacles 30 each adapted to feed nails to the driver, and a swinging part movable in one direction from one of said receptacles to another at the will of the operator and movable in another direction for engaging and delivering 35 a nail from any selected receptacle into driving position to be driven by the driver.

2. In a nail-driving machine, a plurality of nail-holding receptacles converging at their outgoing ends, a nozzle provided with 40 a nail passage and movable to permit said passage to be brought into alinement with the delivery end of any one of the receptacles, means to transfer nails from any receptacle to said passageway, and driving 45 mechanism for driving the nail when received by the nozzle.

3. In a nail-driving machine, the combination with nail-driving mechanism including a driver, of a plurality of raceways, a 50 pick-off, means to shift the position of the pick-off to bring it into position to operate in conjunction with anyone of the raceways, and means to operate the pick off in any one of its positions to cause nails to be delivered 55 singly from the raceway.

4. In a nail driving machine, the combination with a nail driving mechanism, of a hopper comprising a plurality of pockets each having a slot in its bottom, a nail selector or pick-off arranged below said hopper, said hopper and selector being relatively movable to bring said selector into operative relation to any one of said pockets whereby said selector may be projected 65 into the slot in the bottom of said pocket,

and means for projecting the selector into the slot and for retracting the selector.

5. In a nail driving machine, the combination with nail driving mechanism, of a nail hopper having a plurality of pockets 70 each provided with a longitudinal slot in its bottom, a nail selector or pick-off pivoted below said hopper and vertically movable into the slot in one of said pockets, said hopper and said selector being relatively movable to bring the selector into operative relation to any one of said pockets and means for effecting the vertical movement of said selector.

6. In a nail driving machine, the combination with nail driving mechanism, of a nail hopper provided with a plurality of pockets each having a slot in its bottom, a nail selector below said hopper adapted to be moved into the slot in one of said pockets, said hopper and said selector being relatively movable whereby said selector may be brought into operative relation to any one of said pockets, and means for moving said selector into said slot and 90 lengthwise of said slot.

7. In a nail driving machine, means for holding nails in regular order, a vertically stationary nozzle provided with a driver passage, a vertically movable driver having 95 a sudden downward driving movement for driving said nails when received by said nozzle, means under the control of the operator for actuating said driver, and nail-delivering means operated by the movement of 100 the work into nail receiving position, to deliver the nails one by one to said nozzle.

8. In a nail driving machine, a vertically stationary nail receiving nozzle, provided with a driver passage, a driver operating in 105 said passage, means for holding nails in readiness for delivery to said nozzle, a movable work-rest, and means movable relatively to said nozzle and actuated by said work-rest for delivering the nails individually 110 to the nozzle.

9. In a nail driving machine, a nail receiving nozzle, driving means to drive a nail in said nozzle, means for holding nails in readiness for delivery to said nozzle, a work-rest, 115 means actuated by said work-rest for engaging and delivering the nails individually to the nozzle, actuating means for said driving means and means for also causing the work-rest to so actuate said delivering 120 means.

10. A manually operated nail driving machine comprising, in combination, nail driving mechanism, a work rest to engage the upper side of and control the position of the 125 work, a work support to carry the work, said work support and said nail driving mechanism being relatively movable to present the work in position to receive a nail, a swinging pick-off connected to said work 130

- rest to be operated thereby, as the work is presented to the nail driving mechanism, to deliver a nail directly into position to be driven by said nail driving mechanism during the same cycle of operations of the machine, and connections between said work support and said nail driving mechanism whereby the said parts are operated in proper time relation to each other.
11. In a nail driving machine, means for holding nails in regular order so that they may be taken off one by one, a vertically stationary nozzle provided with a driver passage, a driver operating in said passage, means for operating said driver and means operated by the movement of the work into nail receiving position with respect to said nozzle for separating a nail from the line in said nail holding means and delivering it in position to be driven by the driver during that cycle of operations of the machine.
12. In a nail driving machine, nail driving mechanism including a nozzle having a nail receiving passage, nail feeding mechanism, including a pivoted pick-off adapted to engage behind a nail to move the latter bodily into said passage, and means actuated by the movement of the work into nail receiving position to swing the upper end of said pick off and the nail carried thereby over forward into approximate alinement with said passage for positioning the nail in the latter.
13. In a nail driving machine, a hopper provided with a nail passage, a nozzle having a nail receiving passage adapted to aline with said nail passage, a reciprocating device mounted to slide up and down on said nozzle, a pick-off movably mounted on said device in position to engage the nearest nail in said hopper when said device is raised, and relatively stationary means for automatically moving said pick-off and the engaged nail to deliver the latter into driving position in said nozzle.
14. In a nail driving machine, a hopper provided with a nail passage, a nozzle having a nail receiving passage adapted to aline with said nail passage, a reciprocating device mounted to slide up and down on said nozzle, a pick-off movably mounted on said device in position to engage the nearest nail in said hopper when said device is raised, and a trip to swing said pick-off and said nail forward, when said device is raised, to deliver said nail into proper driving position in said nozzle.
15. In a nail driving machine, a hopper provided with a nail passage, a nozzle having a nail receiving passage adapted to aline with said nail passage, a reciprocating device mounted to slide up and down on said nozzle, a pivoted pick off having a point to enter behind the nearest nail when said device is raised, and a trip to swing said
- pick off and said nail forward, when said device is raised, to deliver said nail into proper driving position in said nozzle.
16. In a nail driving machine, a machine head, a reciprocating driver depending from said head, a nozzle movably mounted on the depending portion of said driver for turning movement about the driver as an axis, and means for adjustably locking said nozzle to said head in varying positions.
17. In a nail driving machine, a machine head, a reciprocating driver depending from said head, a nozzle movably mounted to rotate on the depending portion of said driver, and spring locking means for locking said nozzle to said head at various points in its rotation.
18. In a nail driving machine, nail driving mechanism including a pivoted hammer lever, a spring for giving the same its driving impulse, a lifting arm pivoted concentrically of said lever for lifting said lever in opposition to said spring, and an automatic tripping connection between said arm and lever, consisting of a normally projected lifting lug yieldingly carried by one of said parts and movable parallel to the pivotal axis thereof, a radial shoulder on the other part normally engaged by said lug, and a relatively stationary cam surface engaging said lug for moving it out of engagement with said shoulder when the hammer lever is moved to raised position by said arm.
19. In a nail driving machine, nail driving mechanism, a yieldingly mounted work-support, and an operating rod for actuating said nail driving mechanism, said rod movably engaging said work-support, and being provided with a spring connection with said work-support separate from the yielding mounting of the latter for permitting the non-simultaneous movement of said rod and work-support.
20. In a nail driving machine, a machine head and its support, nail driving mechanism, an operating rod for the latter, and a work-support movably mounted upon said machine support and rod, and raised and lowered by the latter, said support and rod being each provided with springs engaging said work-support in opposition to each other.
21. The combination with a nozzle having a driver passage and a nail passage leading to the driver passage, of a raceway to receive nails, a pick-off, and means to move the pick-off transversely to the raceway to cause it to separate the last nail in the raceway from the other nails and then to move said pick-off in the direction of the length of the raceway to deliver the separated nail into the nail passage.
22. The combination with a nozzle having a driver passage and an open-bottomed

nail passage leading to the driver passage, of a raceway to receive nails, a pick-off, and means to cause the pick-off to move vertically to separate the last nail in the raceway from the other nails and then to move in the direction of the length of the raceway to deliver the separated nail into the nail passage, said pick-off occupying the nail passage and forming the bottom thereof during such latter movement and acting to guide the nail into the driver passage.

23. The combination with a nozzle having a driver passage and a nail passage leading thereto, of a raceway to receive nails, a ver-

tically-movable member, a pick-off pivotally sustained thereby, means to move said member vertically to cause the pick-off to separate the last nail in the raceway from the other nails, and means for then causing the pick-off to swing on its pivot to deliver said nail from the raceway to the driver passage.

In testimony whereof, I have signed my name to this specification, in the presence of two subscribing witnesses.

DANIEL E. HALL.
